Massillon, Ohio

Filed July 24, 1962, Ser. No. 212,091

2 Claims. (Cl. 312—39)

The present invention relates to new and useful improvements in material dispensing apparatus and more particularly to a motor driven dispenser for sheet material in roll form such as toilet tissue, paper towels, or the like.

The present application is a continuation-in-part of application Serial Number 195,465, filed May 17, 1962 entitled "Sheet Material Dispenser".

In the past, mechanical dispensers, mostly hand operated, have been suggested for unrolling and dispensing of sheet or web material such as paper towels, waxed paper, tape, tickets, and the like. These devices were generally cumbersome and expensive to build and did not generally present a neat unobtrusive appearance when installed.

It is an object of the present invention to provide a sheet material dispenser that is operated by an electric motor actuated by an accessible hand switch or button.

Another important object of the present invention is to provide an electric tissue dispenser which may be housed entirely within a room wall and which presents a trim neat appearance.

A further object of the invention is to provide a toilet tissue dispenser driven by an electric motor which may be easily swung out from a wall for refilling the paper supply or maintenance of the motor or drive mechanism.

A still further object of the invention is the provision of a motor-driven feed belt assembly for a sheet material dispenser which resiliently engages material being fed and which will not tear or crinkle even delicate material such as toilet tissue.

Another object of the instant invention is the provision of a motor-driven feed belt assembly for a dispenser for perforated sheet material which will permit manual pulling of the material end without tearing intermediate two perforation lines.

A further object of the invention is to provide a motor-driven feed belt assembly for a sheet material dispenser which will insure that manual pulling of the free end of the material will cause tearing thereof within the housing of said dispenser.

It is another object of the invention to provide a chute structure for a motor-driven sheet material dispenser which serves to guide the material from its roll to the discharge opening of the dispenser without folding or fouling in the machine.

Other objects of the invention are to provide a motor-operated sheet material dispenser bearing the above objects in mind which is of relatively simple construction, has a minimum number of parts, is inexpensive to manufacture, and is at all times efficient, reliable, and safe in operation.

For other objects and for a better understanding of the invention, reference may be had to the following detailed description taken in conjunction with the accompanying drawing in which:

FIGURE 1 is a perspective view of the new dispenser of the present invention installed in a tiled bathroom wall;

FIGURE 2 is a side elevational view of the dispenser

2

taken along the line 2—2 of FIGURE 1 and showing the folding of the front cover plate in dotted lines;

FIGURE 3 is a cross-section taken along the line 3—3 of FIGURE 2 with the roll of paper removed; and

FIGURE 4 is a fragmentary cross-section along the lines 3—3 of FIGURE 3.

Reference is now made more specifically to the drawings wherein like numerals designate similar parts throughout the several views and wherein the dispensing device constituting the subject matter of this invention is designated generally at 10 and is shown flush mounted in the usual tiled bathroom wall 11.

The dispenser body is preferably fabricated in the form of a sheet metal box or housing 12 being open at the front and having a cut-away portion at the bottom adjacent the open side. Of course, plastic or wood or other suitable material could be used for the housing if so desired. A mounting flange 13 is welded or otherwise secured around the four sides of the box to permit neat mounting in a wall recess regardless of the accuracy of the wall cut. A front sheet metal cover 14 is hingedly attached to the box in a manner more specifically described in the aforementioned copending application, Serial Number 195,465. By the use of this construction, the entire front cover can be pivoted outwardly and downwardly to the dotted line position of FIGURE 2 to expose all of the operating components for repair and to permit easy reloading of the machine with a new sheet material supply.

In order to permit ease of maintenance and of refilling, all of the mechanical elements of the feed mechanism, including the motor, are attached to the inside of the front cover 14 so as to be accessible upon opening of the cover. The rolled tissue paper or the like, shown at 15, is also received within the front cover section.

Fixed to the inside of the cover 14 as by flanges 16 are two spaced parallel side plates 17 and 18 and a bottom plate 19 which spans and closes off the bottom between the two plates. Within the enclosure defined by these three elements, all of the mechanical components are supported. Formed in each of the side plates 17 and 18 are openings for reception and journalling of the ends of belt roll shafts 20, 21, and 22. A slightly larger hole 23 is also provided in each of plates 17 and 18 for the loose reception of the end of belt roll shaft 24. Further holes are provided in the side plates for reception of motor mounting screws 25 and tension springs, later to be described.

In order to maintain the rigidity and spacing of the side plates 17 and 18, spacer members 28 and 29 are provided adjacent the upper side of the plates and spanning them. Spacer member 28 is preferably of sheet metal and also serves the secondary purpose of acting as a front support plate for the rolled material 15 and prevents it from slipping down into the mechanical moving elements when the roll diameter decreases in size. If desired, yet a further rigidifying sheet metal cross member 30 may be provided at the back of the side plates adjacent the top.

Guide chute 31 receives the sheet material and guides it downwardly to the discharge opening 32 formed in the overhang of the front cover 14. The chute has a general box-like construction of sheet metal or plastic and includes the top plate 33 and the bottom plate 34. If desired, separate side plates may also be used, but the top and bottom plates may be attached directly to the side plates 17 and 18 utilizing them as side members to

enclose the chute. If separate side plates are used, they may flare outwardly adjacent the discharge end. As can be seen from FIGURE 4, the top plate 33 is of greater length than the bottom plate. The entire chute is mounted angularly as shown in FIG. 4 and extends between the side plates 17 and 18 and is attached thereto as by welding or the like. The width of the chute between the two side plates is slightly greater than the width of the sheet material to be dispensed. It has been found that toilet tissue is generally standardized in width at 4½ inches. If the device is to be adapted to dispense such tissue, a preferable width for the chute interior would be 4¾ inches. Each of the top and bottom plates of the chute is provided with roll receiving recesses for the belt rolls generally rectangular in shape as shown at 35. The rearward recesses for the top and bottom belt rolls are at the very edges of the top and bottom chute plates and hence are open at the rear. This facilitates initial feeding of the material.

20 Wooden belt rolls 36, 37, 38, and 39 are fitted securely on the belt roll shafts 20, 21, 22, and 23, which shafts are journaled in and extend through opposite holes as above described in the side plates 17 and 18. The shafts are so positioned that the roll peripheries will extend through the roll receiving recesses 35 in the chute 31. While the rolls are preferably made of wood, hard rubber, plastic and cork are equally effective. The shafts are held from axial displacement by positioning washers or Circlips 40 which may be fitted in annular recesses formed in the shafts.

25 The belt rolls 36 and 39 are of a greater length than the rolls 37 and 38, as can be seen in FIG. 3 and are generally in driving contact with one another. This greater length gives a greater contact area for more efficient drive. An annular belt receiving cut-out is formed in each of the rolls 36 and 39 for reception of feed belts 41 and 42 respectively. Due to this cut-out construction, the belts will be recessed so that their top surfaces are flush with the rolls 36 and 39 and they will not interfere with the friction drive between the rolls.

30 Each of belts 41 and 42 are endless loops of stitched webbing material or rubber. It is also preferable that they be slightly elastic to facilitate assembly on the rolls. The belts pass over the rolls 37 and 38 at the outlet area of the dispenser, which rolls are of approximately the same width as the belts or slightly larger as shown in FIG. 3. As noted from FIGURE 4, the belt runs 41 and 42 pass into chute 31 and are in mating face-to-face engagement. It is within this area that the sheet material is fed.

35 Secured on the end of shaft 20 outward of side plate 18 is a small grooved pulley 43. The pulley may be secured to the shaft by a set screw passing through its hub 44 or by press fitting.

40 In order to provide a resilient downward force of the upper belt roll 39 against the roll 36 so that they cooperate to engage and feed the paper or tissue, means are provided to apply a spring force against the belt roll shaft 24. This means comprises a pair of pivoted pressure bars 45, 46 which are pivoted adjacent one end about roll shaft 22. These bars are mounted on the outside of side plates 17 and 18 and have their other ends connected to the outer ends of roll shaft 24. Since this shaft is free to move slightly in large hole 23, the pressure bars can be moved to cause similar movement of shaft 24. Each pressure bar is provided with a small hole 47 adjacent the connection with shaft 24. A tension spring 48, 49 for each pressure bar has one end engaged in a hole 50 formed in each of the side plates 17 and 18 and the other end engaged in the hole 47. With this structure the belt roll 39 will exert resilient pressure against the roll 36. As can be seen in FIGURE 4, the lower rolls 37 and 38 are not in contact with each other. Because of this construction, when the desired amount of material such as perforated toilet tissue has

been dispensed and is pulled manually by the user, the paper will separate at the perforation closest to the line of contact between rolls 36 and 39 which are held resiliently together. Since the distance from these rolls to the outlet 32 is greater than the distance between perforation lines in the material being dispensed, there will be no loose dangling end external of the dispenser. This presents a more tidy and neat arrangement.

10 Power to drive the dispenser is provided by the use of an electric motor 51 which is secured to either the side plate 17 as shown or the bottom plate 19.

15 This motor may be any commercially available model but is preferably a two speed reversible gear ratio motor. A large drive pulley 52 is secured on the rotor shaft extending outwardly of side plate 17 and is in driving engagement with pulley 43 by means of a rubber drive belt 53.

20 The motor is connected to the 120 volt line and has interposed therein a cut-off safety switch 54 and a push button start and stop switch 55. The safety switch is operable upon opening of the front cover as more fully described in our copending application. The push button 55 is of the conventional spring type and is normally off until depressed. If desired, a reverse switch 56 may be provided on the inside of the box for actuation if for any reason the material should jam up in the chute and it is desired to reverse the drive or wind in.

25 Operation of the dispenser can be readily envisioned. Material, such as toilet tissue in roll form, or even 30 squashed into an oval is dropped into position between the side plates so that it rests on the spacer member 28 and the belt roll 39. The free end of the paper is placed into the upper chute opening adjacent the two rolls 36 and 39 and the drive chain turned by hand so that paper feed is commenced into the chute. The cover is then 35 closed and actuation of the button 55 will cause paper to be fed out of the opening 32 until the button is released. The paper is then grasped and pulled, tearing neatly within the machine.

40 It is anticipated that the instant device will be useful in all applications wherein perforated material is to be dispensed such as paper towels, toilet tissue, wrapping tissue, napkins, etc.

45 While we have shown and described a preferred embodiment of the invention, it is to be understood that the drawings and detailed disclosure are to be construed in an illustrative rather than a limiting sense since various modifications and substitutions of equivalents may be made by those skilled in the art within the scope and 50 spirit of the invention as defined in the appended claims.

55 What we claim as new and desire to protect by Letters Patent of the United States is:

1. A dispenser for sheet material comprising a housing having an open side, a cover normally closing said open side of said housing, means mounted on said cover to support a roll of sheet material, a discharge opening in said cover, a guide chute mounted on said cover to guide said material from said roll to said discharge opening, a pair of upper parallel belt rolls rotatably mounted on said cover above said chute and extending partially into said chute, a pair of lower parallel belt rolls rotatably mounted on said cover below said chute and extending partially into said chute, two endless feed belts, each belt passing through said chute and over one of said belt roll pairs, pressure bar means pivoted adjacent one end to said cover and having the free end thereof in contact with said upper belt roll nearest said roll of sheet material, and resilient means urging said free end of the pressure bar and said upper roll toward one of said lower belt rolls, and motor means mounted on said cover in driving engagement with said last mentioned lower roll, whereby opening of said cover withdraws all of the mechanical components of said dispenser from said housing.

70 2. A dispenser for sheet material as defined in claim 1, wherein said motor means comprises an electric mo-

tor connected by a line to a source of electrical potential, an on-off switch interposed in said line, and safety switch means operative upon opening of said cover to disconnect said motor from said source.
